Attorney.

UNITED STATES PATENT OFFICE.

ARTHUR D. MACKEY, OF LAWRENCE, KANSAS, ASSIGNOR TO L. B. MACKEY.

HOTEL-REGISTER.

SPECIFICATION forming part of Letters Patent No. 399,622, dated March 12, 1889.

Application filed March 26, 1888. Serial No. 268,558. (No model.)

To all whom it may concern:

Be it known that I, ARTHUR D. MACKEY, of Lawrence, Douglas county, Kansas, have invented a new and useful Improvement in 5 Hotel-Registers, of which the following is a full, clear, and exact description, reference being had to the accompanying drawing, forming a part hereof.

My invention relates to certain improvements in hotel-registers; and it may be said to consist in the novel construction of leaves and relative arrangement of matter upon the leaves composing the book, hereinafter set forth, and pointed out in the claims.

15 The object of the invention is to provide a book of this nature which will be more advantageous and serviceable than those heretofore in use.

In the drawing, which illustrates the manner of carrying out my invention, the figure represents a perspective view of the book opened and in position for use.

In describing my invention it will not be necessary to speak of a plurality of pages, 25 leaves, or sheets. Upon the signature page or sheet A, I locate printed lines of words C, and leave signature-spaces D between such printed lines of words, thereby separating the signature-spaces a considerable distance, and 30 thereby enabling the public in general to

more readily read at a glance the names of the registered guests; and they are more especially provided in order that the hotel-clerk, standing as he does behind the counter, may 35 be better enabled to read and recall the name of a guest who has just registered (or who may have registered at any previous time) without turning the register end for end upon the counter and interrupting the guest who

40 is usually looking over the names on the said page at this time, as has heretofore been necessary. Said line of printed words or characters are preferably printed on said signature-page in comparatively small type, and 45 so as to reach across or substantially across said page, and thereby practically answer as guiding-lines for the guests to write upon in registering. These lines of printed words may be made up of any number of words or 50 combination of words that I may desire to use.

To illustrate this construction and arrangement, I will take the registering-space No. 6 upon the signature-page A, in which are written the name and residence of a guest who desires to pay his bill, and the blotter page or 55 sheet B, which is located directly opposite the signature-page, and upon the face of which are arranged blank squares or spaces E, which correspond in number to the spaces D upon the signature-page, and which are also serially numbered to correspond with the numbers on the opposite signature-page, and in the space 6 on said blotter-page the clerk charges the guest with any extras he may have ordered during his stay at the hotel, and 60 when the guest is to leave the clerk can use this particular space (on the blotter-page) upon which to figure the whole amount of bill against the guest, and the guest can at once see if it be right and proper or erroneous, the 65 names on said spaces E being arranged in an inverted position with relation to the printed lines of words and numbers on the signature-page, thus enabling the clerk to figure in the proper space on the blotter without turning 70 the register, as before stated. It will thus be seen that guest No. 6 (by which title the clerk will designate him in using my invention) is charged in space 6 upon the blotter-page with 75 \$3.10.

80 The blank spaces on blotter-page B can be ruled or marked off any desired way, which will accomplish the purpose hereinbefore stated.

Having thus described my invention, what 85 I claim is—

1. A hotel-register comprising signature-sheets and blotter-sheets alternately arranged, the pages of the signature-sheets having horizontal printed signature-lines of words, and 90 the spaces between said lines being serially numbered, the pages of the blotter-sheets having spaces formed by horizontal and vertical lines and the spaces serially numbered in duplicate to correspond with the numbered 95 spaces of the signature-pages, all combined substantially as set forth.

2. A hotel-register comprising signature-sheets and blotter-sheets alternately arranged, the pages of the signature-sheets having hori- 100

zontal printed signature-lines of words, and
the spaces between the said lines being se-
rially numbered, the pages of the blotter-
sheets having spaces formed by horizontal
5 and vertical lines, and the spaces serially
numbered in duplicate to correspond with the
numbered spaces of the signature-pages, the
said signature-sheets and blotter-sheets being
arranged in reverse order to each other, and

combined as set forth, and for the purpose to
specified.

In testimony whereof I affix my signature in
presence of two witnesses.

ARTHUR D. MACKEY.
